UNITED STATES PATENT OFFICE.

RICHARD J. EDWARDS, OF GALENA, ILLINOIS.

PIPE-COUPING.

SPECIFICATION forming part of Letters Patent No. 400,759, dated April 2, 1889.

Application filed October 23, 1888. Serial No. 288,957. (No model.)

To all whom it may concern:

Be it known that I, RICHARD J. EDWARDS, a citizen of the United States, residing at Galena, in the county of Jo Daviess and State of Illinois, have invented certain new and useful Improvements in Combined Car and Air-Brake Pipe-Couplings, of which the following is a specification, reference being had therein to the accompanying drawings, in

10 which—

Figure 1 represents a side elevation of the adjacent ends of two freight-cars coupled together according to my invention; Fig. 2, a 15 sectional view of a portion of one of the cars, showing the means for uncoupling air-pipes and cutting off the air; Fig. 3, a similar sectional view showing the car-coupling devices; Fig. 4, a detail plan view of the air-pipe or 20 hose coupling; Fig. 5, a detail plan view of one of the coupling-sections; Fig. 6, a side elevation of the same; Fig. 7, a side elevation 25 of the valve in the air-brake pipe.

This invention has relation to that class of car-couplings covered by a patent issued to me on the 17th day of April, 1888, and numbered 381,349; and it has for its objects, mainly, to provide such couplers with simple and improved means, whereby the air-brake 30 hose-couplings are uncoupled and the shut-off cock closed at the same time and by the same movement that operates the car-coupling devices, as will be more fully hereinafter set forth.

In the accompanying drawings, A A' represent 35 the adjacent ends of two freight-cars; B, the usual or any improved draw-bars provided with the draw-heads C; D, the upper coupling-pins attached to the draw-heads by means of chains; E, the lower coupling-pins 40 inserted in the lower pin-apertures in the draw-head and supported by means of a pivoted operating-lever, F; G, the sliding dog in the draw-head, which is adapted to support the coupling-pin; H, the pivoted lever in a 45 recess in the draw-head adapted to operate the said sliding dog; I, the depending gravitating rod hung upon the said lever H and adapted to operate it, and J the transverse operating-shaft journaled in the beams of 50 the car and provided with a crank-arm, J', to

operate the lever F and operating-handles J'' at its end at the sides of the car.

The parts are constructed and operated in substantially the same manner as in my former patent above mentioned, and a more 55 minute description is deemed unnecessary in this specification. There are, however, a few important parts which I will now point out. In this device the sliding dog is not operated automatically to drop the pin, as in the former 60 patent, but it is operated by hand, the lever H being placed back in a recess in the draw-head out of the way, so that the coupling-link will not strike against it upon entering. I prefer this construction to that shown in my 65 former patent, in that it will preclude the possibility of the lever H becoming broken or injured in any way. In this invention I also place on the crank-arm J' a loose anti-friction grooved roller, by means of which the 70 lever F is elevated. This roller permits the lever to be elevated in a steadier and smoother manner, as is evident. I also provide the under side of the draw-head with depending integral guards C', to prevent the pin E, rod I, 75 and lever F from being injured in any way.

I will now describe the devices employed for detaching or uncoupling the hose-couplings of the air-brakes.

The letter K designates the main air-pipe 80 of the air-brakes provided with the usual valves or stop-cocks, a, near the ends of the cars and connected to the flexible hose-sections K'. The stop-cock or valve a is operated by means of a lever, b, secured to the 85 stem of the plug of the cock, this lever b being provided with a leaf-spring, c. When this arm or lever b is in a horizontal position, as shown in Fig. 2, the passage is closed, and when turned down to the position shown in 90 Fig. 7 the passage through the air-pipe is open. This valve-arm b is turned up to close the valve by means of a crank-arm, d, on the rock-shaft J, the arm d bearing against the yielding spring c to prevent and reduce 95 concussion or wear of the parts. It is evident that the spring c may be omitted and the crank-arm made to bear directly against the arm or lever b without departing from my invention. The crank-arm d is so placed on the 100

rock-shaft that when the cars are uncoupled the arm will at the same time be turned up sufficiently high to close the stop-cock or cut-off, thus preventing the escape of compressed air.

The ends of the flexible hose-sections K' are provided with twin coupling devices L, provided with suitable interlocking flanged lugs.

10 I prefer to use in connection with my invention the "Westinghouse" detachable coupling, and I have shown that construction of device in my drawings. This hose-coupling is uncoupled by a partial revolution of 15 its two sections, and for that reason I prefer to use it. It is evident, however, that I may employ other detachable hose-couplings that uncouple in substantially the same manner without departing from the invention.

20 Secured on the outer faces or sides of the sections L of the hose-coupling by means of screw-bolts or cast integral therewith are upwardly and forwardly projecting rigid arms L', which are connected by means of suitable 25 chains, f, to crank-arms e on the rock-shafts J, as shown. The chains f pass over pulleys g, secured to the bottoms of the cars.

It will be observed that by drawing on either 30 one of the chains f, by means of one of the rock-shafts and crank-arms, the coupling-sections L L will be elevated and rotated a sufficient distance to become disengaged from each other, as shown in Fig. 2.

The crank-arms e are so located on the rock- 35 shafts that the hose-couplings may be detached by the same movement and at approximately the same time that the cars are uncoupled and stop-cock a closed. It will therefore be observed that by one partial revolution of one of the rock-shafts the whole operation of uncoupling is accomplished.

Among the many advantages derived from 45 using my invention is that the whole operation of uncoupling the cars and air-brake couplings and closing air-pipes may be accomplished without the slightest danger as well when the cars are in motion or standing still.

It will be observed that I may use my invention with equal advantage for uncoupling steam-conveying pipes.

To uncouple the cars and shut the stop-cocks a, the levers or handles J" are moved forward, and to uncouple the hose-couplings 55 they are moved in the reverse direction.

Having thus fully described my invention, what I claim as new, and desire to secure by Letters Patent, is—

1. The combination of the cars, transverse crank-shafts journaled upon the cars, conducting-pipes upon the cars provided with flexible hose-sections, pipe-couplings on the ends of these flexible sections, these couplings being provided with interlocking lugs and upwardly-extending arms, and chains connecting the upwardly-extending arms with the respective crank-shafts on the cars, whereby the couplings may be uncoupled, whether the cars be in motion or at rest, substantially as described. 60

2. The combination, with the cars provided with draw-bars and draw-heads, of the coupling devices, multiple crank-shafts journaled on the cars and adapted to operate the uncoupling devices, the air-pipes provided with the 75 flexible sections, the pipe-couplings provided with interlocking lugs and arms, chains connecting these arms with the cranks on the respective crank-shafts, valves in the air-pipes, arms on the stems of these valves, these arms 80 being adapted to be operated by cranks on the crank-shafts, whereby by a single movement of one of the crank-shafts the coupling devices may be uncoupled, the pipe-couplings uncoupled, and the valves in the air-pipes 85 closed, substantially as described.

3. The combination, with the cars, of the multiple crank-shafts journaled in the cars and provided with operating-handles, the air-pipes provided with stop-cocks, arms on the 90 stems of these cocks, these arms being adapted to be operated by the cranks of the crank-shafts, flexible hose-sections on the ends of the air-pipes, coupling-sections on the ends of these flexible sections, these coupling-sections 95 being provided with interlocking lugs and rigid arms, and the chain for connecting these rigid arms with the respective crank-shafts, whereby the said stop-cocks may be closed and the hose-sections detached at one operation, substantially as described. 100

In testimony whereof I affix my signature in presence of two witnesses.

RICHARD J. EDWARDS.
